UNITED STATES PATENT OFFICE.

GEORGE W. KESSLER, OF ROCK VALLEY, IOWA.

CLAMPING DEVICE FOR OIL BUCKETS.

Application filed September 21, 1922. Serial No. 589,730.

To all whom it may concern:

Be it known that I, GEORGE W. KESSLER, a citizen of the United States, and a resident of Rock Valley, in the county of Sioux 5 and State of Iowa, have invented certain new and useful Improvements in Clamping Devices for Oil Buckets, of which the following is a specification.

An object of my invention is to provide 10 a device for clamping oil buckets in place in their containing box on the rear of an oil truck.

My invention is designed to eliminate 15 wear upon the box by the movement of the buckets within, by preventing the movement of the buckets.

Another object is to prevent the battering 20 of the buckets caused by their striking together.

With these and other objects in view, 25 my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a rear elevation of a bucket-retaining box with a pair of buckets therein, 30 held in place by my improved bucket clamp in operative position.

Fig. 2 is a similar view, the clamp being shown in inoperative position.

Fig. 3 is a sectional view through the 35 box showing the clamp in operative position.

Fig. 4 is a similar sectional view showing the clamp in inoperative position, and

Fig. 5 shows a modified form of the clamp 40 yoke.

The ordinary oil delivery truck in general use is made as a tank and at the rear carries a pair of oil buckets which are used to convey the oil or gasoline from the tank to the oil can or gasoline barrel of the customer. These buckets are carried, while the truck is travelling, in a cabinet or containing box at the rear of the truck.

I have found that the jolting of the truck 50 will cause the buckets to move about in the box, impinging against each other, jolting against the sides of the box, and scraping the bottom. As a result, the buckets become 55 badly dented and worn, and their capacity decreases as a result of the sides being bent inwardly. The average life of

the buckets is thus comparatively short, and the box soon becomes badly worn to such an extent that a new one is necessary.

To prevent this wear it is my purpose to 60 provide a clamping device which will securely hold them in place.

In general, my invention may be embodied in a clamping yoke adapted to engage the tops of the cans, to be held in 65 operative position by a latch, the yoke being mounted on pivoted arms, and having resilient means for moving it to inoperative position when the latch is released.

In Fig. 1 I have shown, generally, a rear 70 view of a bucket-retaining box, in which the numeral, 10, indicates the top of the box, and the numeral, 11, the back thereof. The buckets are indicated in dotted lines at C, only the tops thereof being shown. 75

Ordinarily there are two buckets which are received in the box side by side, as shown in Fig. 1, in which the box is viewed from the rear of the truck. The yoke, R, extends between the buckets and engages the 80 tops thereof, as shown in Fig. 1.

The yoke, R, is preferably formed of an angle bar, and is supported by the arms, A, which are riveted or otherwise secured to the lower flange of the yoke. Hinges, B, 85 serve to connect the arms, A, to the rear wall, 11, of the box.

I provide a latch, D, which serves to lock the yoke, R, against the buckets. The latch comprises the arm, 12, hinged at 90 to the top, 10, of the box. By means of a slot, 14, in the arm, 12, and bolts, 15, the latch proper, indicated generally at 16, is adjustably secured to the arm, 12, being 95 slidably longitudinally thereon.

The member, 16, has an offset portion forming a shoulder, 17, which is inclined from the perpendicular, as shown. The member, 16, terminates in a downwardly-projecting finger, 18, which serves as a 100 handle.

When the clamping device is not in use, the parts are held in raised position in the corner of the box, as illustrated in Fig. 4. The spring, 5, serves to draw the latch inwardly and upwardly, and the latch engages the yoke, R, and pushes it to the position shown. 105

When the yoke, R, is drawn downwardly against the latch, the latch will be pushed 110 outwardly till the yoke has slipped under the shoulder, 17, when the latch will be

drawn inwardly by the spring, S, and the inclined shoulder, 17, will force the yoke down against the buckets, C, so as to hold them securely against the bottom of the box.

5. When the latch is drawn outwardly, the spring, S^a, which connects the yoke and latch as shown, will draw the yoke upwardly to a position where its inclination relative to the latch will allow it to be moved upwardly under the pressure of the latch against it.

It will be seen from the foregoing that the clamp may be brought into operation by merely placing the hand upon the yoke and drawing it downwardly. In order to cause the parts to resume inoperative position, the latch is simply drawn outwardly sufficiently to release the yoke from the shoulder, 17, and then released.

10. In Fig. 7, I have shown a modified form of the yoke, in which the yoke, R^a, has pivoted to its ends the clamp jaws, R^b. The jaws, R^b, and the clamp jaws, R, are faced underneath with leather, 20.

15. It will be seen that my device is semi-automatic in its operation, the parts being almost entirely controlled by springs. This feature increases the utility of the device greatly and renders it more desirable.

20. The parts may be adjusted to fit different sizes of boxes.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

25. I claim as my invention:

1. In a device of the class described to be used in combination with a bucket-retaining box, a yoke and a latch, each being hinged at points spaced from each other and positioned so that the paths of the yoke and the outer portion of the latch cross each other at a point where the yoke is in position to engage a bucket in the box, means on the latch to hold the yoke in such position, the latch being positioned to engage the yoke and move it to inoperative position, and resilient means to move the latch to inoperative position.

2. In a device of the class described to be used in combination with a bucket-retaining box, a yoke and a latch, each being hinged at points spaced from each other and positioned so that the paths of the yoke and the outer portion of the latch cross each other at a point where the yoke is in position to engage a bucket in the box, means on the latch to hold the yoke in such position, the latch being positioned to engage the yoke and move it to inoperative position when the yoke has swung across the path of move-

ment of the latch, means for moving the yoke across the path of movement of the latch when the latch is released, and resilient means to move the latch to inoperative position.

3. In a device of the class described, a yoke and a latch pivoted on axes spaced from each other for swinging motion toward the plane joining their axes, the yoke being normally positioned between the latch and said plane, resilient means tending to move the latch toward said plane, and means on the latch to lock the yoke and latch against movement toward said plane when the yoke has been moved away from said plane to a predetermined position.

4. In a device of the class described, a yoke and a latch pivoted on axes spaced from each other for swinging motion toward the plane joining their axes, the yoke being normally positioned between the latch and said plane, resilient means tending to move the latch toward said plane, means on the latch to lock the yoke and latch against movement toward said plane when the yoke has been moved away from said plane to a predetermined position, and resilient means tending to move the yoke toward said plane when in the said predetermined position.

5. In a device of the class described to be used in combination with a bucket-retaining box, a yoke having a portion adapted to engage the buckets and a latch, each being hinged at points spaced from each other and positioned so that the paths of the engaging portion of the yoke and the outer portion of the latch cross each other at a point where the yoke is in position to engage a bucket in the box, means on the latch to hold the yoke in such position, and resilient means to move the latch and yoke to inoperative position.

6. In a device of the class described to be used in combination with a bucket-retaining box, a yoke hinged to the box for movement from position engaging a bucket in the box to inoperative position, a latch hinged to the box in position to engage the yoke when the yoke is in engaging position and adapted, when released from such engagement with the yoke, to move the yoke to inoperative position, and resilient means to remove the latch toward such position.

7. In a device of the class described to be used in combination with a bucket-retaining box, a yoke and a latch, each being hinged to the box at axes spaced from each other and adapted to swing toward the plane joining their axes, the latch being adapted to engage the yoke when the yoke has been moved away from said plane to a predetermined position, and resilient means for moving the yoke and latch toward said plane when released from mutual engagement in said predetermined position.

8. In a device of the class described to be used in combination with a bucket-retaining box, having buckets therein, a yoke hinged to the box and adapted to swing from position engaging the buckets to inoperative position where it is substantially removed from the vicinity of the buckets, and a spring-urged latch adapted to lock the yoke in engaging position and to engage the yoke when released from said locking position so as to move it toward inoperative position.
- 5

Signed at Rock Valley, in the county of Sioux and State of Iowa, this 30 day of April 1924.

GEORGE W. KESSLER.
